HOUSED SPARK-OVER GAP

Leo Pummer, Chicago, Ill., assignor to McGraw Electric Company, Milwaukee, Wis., a corporation of Delaware

Application April 11, 1952, Serial No. 281,714

3 Claims. (Cl. 313—231)

1

This invention relates to improvements in a housed spark-over gap.

It has been customary to provide lightning arresters of the expulsion or valve type with a spark-over gap located on the line side of the arrester for the purpose of isolating the arrester from the line under normal operating conditions in the circuit protected thereby.

Frequently, these gaps have been exposed, especially when used with expulsion arresters, so that they might be bridged by some object, such as birds or an accumulation of ice, and thus permit flow of current to ground through arresters.

Attempts have been made to enclose the gaps, but this practice has led to the deposit of condensed metallic vapors on the walls of the enclosure and the establishment of leakage paths between the gap electrodes.

Thus, the removal of one source of trouble merely introduced another source of trouble.

It is an object of this invention to provide a housing for a gap in which metallic vapors generated by an arc are expelled from the housing and prevented from forming leakage paths on the walls of the housing between the electrodes therein.

Another more specific object is to provide a housing having an arcing chamber in which the gap is disposed more nearly approximate to the expulsion end of the chamber and the other end of the chamber is closed to provide an air pocket across which one of the electrodes extends, the air pocket being proportionally dimensioned to provide an air cushion that aids in the expulsion action and prevents metallic vapors from collecting on the walls of the chamber within the area of the pocket.

Other specific novel features will be disclosed as the description progresses.

Fig. 1 is a view in elevation, partly in section, illustrating a combined gap device and arrester.

Fig. 2 is a sectional view of the gap device taken on the vertical axis thereof.

Fig. 3 is a plan view of the gap as viewed from above Fig. 2.

Fig. 4 is a transverse section taken on the line 4—4 in Fig. 2.

Details of the construction of the arrester A shown in Fig. 1 are not developed in the drawings, since they are well-known in the art. It is sufficient to note that it is of the expulsion type and is provided with a terminal rod 1 that extends outwardly of the top of the insulator housing 2 which usually is composed of porcelain. As indicated in Fig. 2 the protruding end 3 of the rod is threaded.

10 The gap device G embodies a housing 4 which is preferably porcelain or glass, but may be composed of other suitable insulating material. In the drawings, the housing 4 is represented as cylindrical to provide an enlarged air and arcing chamber 5 terminating at the lower end in an enlarged shallow bore 6 to form an annular seat 7 and terminating at the upper end in restricted cylindrical bore 8 within the knob portion 9 of the housing 4.

15 Two apertures 10 and 11, disposed at substantially 90° relative to each other, extend through the knob portion 9 radially of the restricted bore 8. The aperture 10 as indicated in Fig. 2 is preferably slanted downwardly and outwardly of the bore 8. The wall of the bore 8 is provided with two indentations 12 and 13 diametrically opposite the apertures 10 and 11 respectively.

20 Socketed in the bore 8 is a cylindrical terminal block 14 having an axially extending opening 15, a transverse aperture 16 normal to the opening 15, and a threaded aperture 17 registering with the aperture 10 in the knob portion 9. A clamping screw 18 is threaded into the aperture 17 and extends to the aperture 16 for engagement with a conductor 19 shown only in Fig. 1. The conductor aperture 16 is axially in register with the opening 11 in the knob 9 to facilitate insertion of the conductor.

25 The terminal block 14 is anchored in the bore 8, centrally thereof by any suitable material 20 such as cement or a low melting metal alloy, which material flows into the recesses 12 and 13 and thereby is firmly fixed in the bore 8. Obviously, the apertures 16 and 17 in the block 14 and apertures 10 and 11 in the insulator knob 9 will of necessity be closed to the entrance of the material 20 while the block is being secured in position.

30 An elongated electrode 21 having an arcing head 22 at one end and a knurled periphery 23 at the other end, is mounted on the block 14 with the knurled end in push fit engagement with the opening 15 in the block. This arrangement permits axial adjustment of the electrode 21 in the opening 15 to obtain accurate adjustment of the gap between the head 22 and the electrode head 24 on the mounting cap 25.

35 The mounting cap 25 comprises a metal plate with a series of openings 26 arranged circumferentially about the head 24 and is anchored against the annular shoulder 7 in the housing 4 by means of any suitable material 27. As indicated in Fig. 2, the head 24 includes a threaded recess 28 which engages the threaded end 3 on the rod 1 of 55 the arrester. A resilient washer 29 is clamped

between the cap 25 and the arrester housing 2 and serves to seal the upper end of the arrester.

From the foregoing disclosure, it will be observed that the gap device includes a housing closed at the upper terminal end and open at its lower end for expulsion of gases when the air in the chamber is expanded in response to heat generated by an arc across the gap. It will also be noted that the gap area between the electrodes is located in the region of the cap which includes the expulsion opening and in comparison is relatively remote from the closed end of the housing. As a result, any metal vapor generated by an arc between the electrodes will be projected into the region adjacent the cap and that the air above that region will be expanded by the heat of the arc and will force the air containing the vaporized metal out of the housing through the openings 26. Any condensation of the vaporized metal that may collect on the walls of the housing will be confined to the surface immediately adjacent the arcing area and virtually none will reach the walls of the housing above that area.

Since metallic vapor will be prevented from deposition on most of the wall of the chamber, it will be obvious that arcing between the electrodes will not produce a condition within the chamber which will establish leakage paths over the surface of the walls of the chamber between the terminal block 14 and the cap 25.

The arrangement of the elements is a novel contribution in that it overcomes two serious problems, namely conceals the gap electrodes and prevents formation of leakage paths between the gap electrodes.

I claim:

1. In a spark-over gap device, the combination with a cup-like housing composed of insulating material and enclosing an elongated arcing chamber open at one end and closed at the other end, of an apertured electrode plate secured in said open end, a terminal block secured in the closed end and including conductor receiving and clamping means accessible from the exterior 45 of said housing, and an elongated electrode ex-

tending from said block adjacent the closed end of said housing to a point adjacent said plate and the apertures therein, the chamber in said housing being proportioned so that a major portion thereof is disposed about the length of said electrode and a minor portion surrounds the gap between said electrode and plate.

2. In a spark-over gap device, the combination with an insulating housing open at one end and closed at the other, of a pair of electrodes in said housing forming a spark-over gap adjacent the open end thereof, one of said electrodes extending to the closed end of said housing and including connector means accessible exteriorly at said closed end, the major portion of the chamber in said housing surrounding said one of said electrodes being disposed between said gap and said closed end and the minor portion of said chamber surrounding said gap adjacent said open end.

3. In a spark-over gap device, the combination with an insulating housing comprising a cup-like member having an elongated chamber open at one end, an annular shoulder interiorly adjacent said open end, a restricted bore at the other end of said chamber having a pair of radial openings at substantially 90° relative to each other and extending to the exterior of the housing, of an apertured mounting cap mounted on said annular shoulder and secured thereto, said mounting cap having interiorly of said chamber an arcing head and exteriorly a threaded recess, a terminal block in said restricted bore secured therein in sealed relation thereto and having a conductor receiving aperture registering with one of said radial openings and a clamping bolt registering with the other radial aperture and extending to said conductor receiving aperture, said block having a recess interiorly of said housing directly above said arcing head, and an elongated electrode having one end in push fit engagement with recess and an arcing head at its other end adjacent said arcing head.
